UNITED STATES PATENT OFFICE.

BERNHARD LEPPERHOFF, OF BARMEN, GERMANY, ASSIGNOR TO SUTRO BROS. BRAID COMPANY, OF NEW YORK, N. Y., A CORPORATION OF NEW YORK.

SWITCH FOR PLAITING AND BRAIDING MACHINES.

No. 886,825.

Specification of Letters Patent.

Patented May 5, 1908.

Application filed February 6, 1906. Serial No. 299,790.

To all whom it may concern:

Be it known that I, BERNHARD LEPPERHOFF, a subject of the Emperor of Germany, residing at Jaegerstrasse 77, Barmen, Germany, have invented new and useful Improvements in Switches for Plaiting and Braiding Machines, of which the following is a specification.

The object of this invention is to provide a substitute for the vibrating tongue switches in plaiting and braiding machines. This invention can also be practically applied when in applying tongue switches difficulties are encountered in consequence of want of room.

15 This invention is set forth in the following specification and claim and illustrated in the annexed drawing, in which:

Figure 1 is a plan view of a braiding machine embodying this invention. Fig. 2 is a side view of Fig. 1. Fig. 3 is a front view of Fig. 1.

Between plates 1, 1, 2, 2, is applied a frog or heart shaped piece or plate 3. Two slides 4, 4, are shown sunk or depressed so as to be flush with the upper face of piece 3. These slides by suitable means can be so shifted as to contact with plate 1, or with the opposite plate 2 as required. They are so shaped as to form in each of said cases a complement or completion of the respective race way or path for the bobbin carriers and correspondingly guide the oncoming bobbin carrier. The slide at the right in contact with plate 1 and the slide at the left in contact with plate 2 the oncoming bobbin carrier at the right is led to the outer plate, the one at the left to the inner plate. The reciprocations of the slides 4 will be understood from Figs. 2 and 3.

On column 5 are fulcrumed two levers 6

and 7 at the screws 8. These levers at their upper ends pass through slits in the frog or plate 3 and engage or enter seats in the slides 4 to actuate the latter. The swing of the levers under the influence of the jacquard machine is converted into a reciprocating movement of the slides 4. The latter are guided at their straight edges by the corresponding edges of the frog. Additional guiding and security are provided by the small screws 9 extended into slots in the slides.

As shown each individual slide can be actuated by itself by the jacquard machine.

What I claim as new and desire to secure by Letters Patent, is:

1. In a machine of the class described, the combination with plates suitably spaced to form a raceway therebetween, of a frog piece applied between the plates, slides seated against the sides of and having their top faces flush with the top of the frog piece, and levers for moving the slides rectilinearly back and forth between the plates.
2. In a machine of the class described, the combination with plates suitably spaced to form a raceway therebetween, of a frog piece fixed between the plates, slides having pin and slot connections with the frog piece to be rectilinearly guided thereon to form switches, and levers for actuating the slides.

In testimony whereof I have hereunto set my hand in the presence of two subscribing witnesses.

BERNHARD LEPPERHOFF.
